THERMOSTATIALLY CONTROLLED MECHANISM

Original Filed Nov. 19, 1924 3 Sheets-Sheet 3

Inventor:

Oscar C. Schroeder,
By his wife, Lee, Britton Miller,
Attest

UNITED STATES PATENT OFFICE.

OSCAR C. SCHROEDER, OF CHICAGO, ILLINOIS.

THERMOSTATICALLY-CONTROLLED MECHANISM.

Original application filed November 19, 1924, Serial No. 750,851. Divided and this application filed December 21, 1925. Serial No. 76,798.

My invention relates, more particularly, to thermostatically controlled electrical mechanism, it having been devised for embodiment, more particularly, though not necessarily, in burner structures, the present application being a division of my pending application Serial No. 750,851, filed November 19, 1924.

My primary objects are to provide a novel, simple, economical, and positively operating construction of thermostatically controlled mechanism; to provide for the automatic arresting of the flow of fuel to the burner, in case the pilot light thereof becomes extinguished, thereby preventing flooding, and other objects as will be manifest from the following description:

I have chosen to illustrate my invention as embodied in an oil burner structure, involving as an element thereof, a power device through the medium of which the supplying of the fuel to the burner is controlled, the fuel in this instance being oil and the power device an electric motor, a description of the accompanying drawings being as follows:

Figure 1 is a view in elevation, partly sectional, of an oil burner embodying my improved thermostatically-controlled switch mechanism. Figure 2 is an enlarged view in vertical sectional elevation of my improved thermostatically-controlled switch mechanism operating in connection with the pilot light for a burner, the parts being shown in a position in which the supplying of fuel to the burner is arrested, and the section being taken at the line 2 on Fig. 1 and viewed in the direction of the arrow. Figure 3 is a fragmentary view, like Fig. 2, of a portion of the structure shown therein, the parts being shown in the position they assume when the pilot light is burning and fuel is being supplied to the main burner. Figure 4 is a view in elevation of a detail of the switch mechanism forming a part of the structure. Figure 5 is an enlarged section taken at the line 5 on Fig. 3 and viewed in the direction of the arrow; and Figure 6, a view in side elevation of the portion of the structure shown in Fig. 3, viewing it from a position normal to that from which Fig. 3 is viewed.

Referring to the particular, illustrated, installation in connection with which my improved thermostatic mechanism is employed, the burner proper is represented at 7, the

burner shown, which is of a type well known in the art, employing oil as the fuel, the supplying of which to the outlet of the burner, from any suitable source thereof through a pipe 8 is controlled by an electric motor 9. Located adjacent the burner structure referred to is a pilot light structure for igniting the fuel issuing from the burner, this pilot light structure being represented generally at 10 and shown as involving a tubular member 11 carried by the main body of the burner structure and surmounted by a hollow cap 12 containing a centrally disposed opening 13 in its cap and a gas outlet tube 14 communicating at its lower end with a gas passage 15 located in the upper portion of a hollow supporting housing member 16 shown as connected with the tubular member 11 by screws 17 and engaging an upright post 18 rising from a stationary pan member 19 supported on the posts 20 of the burner structure. The passage 15 communicates with a pipe 21 which leads to any suitable source of gas supply, as, for example, the ordinary service-supply pipe. The tube 14 extends centrally of the tubular member 11 and part way upwardly into the latter as shown. When the gas flowing from the tube 19 is ignited a flame is produced which is caused to become contacted by the fuel issuing from the burner 7 for igniting the fuel which thereafter burns at the burner 7 until the motor 9 is stopped. The starting and stopping of the motor 9, for the purpose above stated, is controlled through the medium of a switch represented generally at 22 and controlled by thermostatic mechanism co-operating with the pilot light.

The switch device illustrated, and which as to its general features is of a well-known type, comprises an air-tight glass tube 23 located in the housing 16 and partially filled with a current-conducting fluid as for example mercury, represented at 24. The tube 23 contains in its upper wall, adjacent one end, two electrical contacts 25 and 26 which are insulated from each other and sealed in the tube, these contacts being connected, respectively, with current conducting wires 27 and 28 leading from the fixed sections 29 and 30, respectively, of plug-in switches positioned in the housing 16, a wire 31 leading directly from the section 29 to the section 110

30. The removable portions of these plugs are represented as 32 and 33, respectively, the section 32 being connected with the wires 34 and 35 leading from the source of electric current, and the section 33 containing the wires (not shown) which connect with the terminals of the motor 9.

The tube 23 is mounted in a clip device 36 presenting spring arms 37, 38, 39 and 40, 10 at its ends and sides which yieldingly embrace the tube 23 and form a support for the latter, the arm 38 containing a slot 41 to receive the sealing tip 42 of the tube 23. The supporting clip 36 is supported on the lower, 15 inturned, ends 43 and 44 of yokes 45 and 46 forming the lower ends of levers 47 and 48, respectively, fulcrumed between their ends, as represented at 49 and 50, respectively, on lugs 51 and 52 provided on the member 20 16. The connections between the yokes 45 and 46 and the clip are pivotal, as represented at 53 and 54, respectively, these connections being at outwardly and downwardly turned arms 55 provided on the clip at 25 opposite sides thereof, the levers 47 and 48 being so proportioned and arranged, as shown that the pivots 53 and 54 extend in 30 different horizontal planes and in one position of the parts, namely, that shown in Fig. 2 wherein the tube 23 inclines downwardly to the left and the mercury 24 is out of engagement with the contacts 25 and 26, the lower pivot 53 extends to the right of the vertical plane occupied by the pivot 54, 35 and when in another position, namely, that shown in Fig. 3 in which the tube 23 inclines downwardly to the right and the mercury is in engagement with the contacts 25 and 26, the pivot 53 extends to the left of such vertical plane. The position 40 occupied by the tube 23, and which determines the making or breaking of the circuit for the motor 9, thus depends upon the position to which the levers 47 and 48 are rocked on their pivotal supports.

Co-operating with the levers 47 and 48 and controlling the position thereof, are 50 thermostatic bars 56 which are secured at their lower ends to the structure 16 and extend upwardly alongside of the gas outlet pipe 14 and upwardly through a tube 57 supported on the member 16 and forming a mixing chamber. The upper ends of the bars 56 are provided with outturned portions 55 extending above the tube 57 and containing apertures 59 through which upwardly extending pins 60 provided on the extreme upper ends of the levers 47 and 48 loosely extend. The bars 56 are each formed of strips 61 and 62 of metal having different 60 coefficients of expansion, the material of which strips 61 are composed having a lower coefficient of expansion than the material composing the strips 62. The parts just described are so constructed and arranged

that when the bars 56 are subjected to the heat of the flame at the pilot burner, they will assume the outwardly deflected position represented in Fig. 3, due to the distorting effect on these bars produced by the unequal expansion of the strips 61 and 62 of which they are formed, and the levers 47 and 48 will assume the position shown in this figure, in which position the tube 23 inclines downwardly to the right in this figure and the mercury 24 is in engagement with the contacts 25 and 26, the bars 56 remaining in such outwardly diverging condition and the levers 47 and 48 and tube 23 remaining in the position just referred to, as long as 70 the pilot light is burning. Upon the extinguishment of the flame at the pilot light, the bars 56 quickly return to the position shown in Fig. 2, thereby rocking the levers 47 and 48 to the position shown in this figure, with the result of rocking the tube 23 to a position in which it inclines downwardly to the left and the mercury flows out of 80 engagement with the contacts 45 and 46.

The operation of the structure shown is 90 as follows:

Assuming that the parts of the structure are in the position shown in Figs. 1 and 2, in which the switch of which the tube 23 is a part, is open and consequently no fuel is 95 being supplied to the burner 7, the operator starts the burner by opening the pilot tube 14 to the supply of gas furnished through the pipe 21, as by opening a valve (not shown) interposed in the gas line and igniting the gas at this tube, whereby the bars 56 become heated and rock the levers 47 and 48 to the position shown in Fig. 3, which results in the closing of the switch controlling the motor 9, which latter thereupon starts into operation and supplies combustible fuel to the burner 7 which is ignited by the flame at the pilot light. Should the pilot light become extinguished the thermostatic bars 56, upon losing their heat, swing 100 inwardly toward each other and rock the levers 47 and 48 to the position shown in Fig. 2 in which position the switch controlled thereby is open. It will, therefore, be noted that provision is made for automatically discontinuing the supply of 110 fuel to the burner 7 should the pilot light become extinguished, and thus danger of accidentally flooding the burner with fuel is reduced to the minimum.

By providing the thermostat mechanism as described, the mechanism is caused to be capable of very quick action and is rendered very responsive in action. Furthermore, the device presents practically no time lag, so 115 that practically as soon as the pilot light becomes extinguished, the controlling circuit for the motor 9 is opened.

While I have illustrated and described a particular construction embodying my in- 120

vention, I do not wish to be understood as intending to limit it thereto, as the same may be variously modified and altered without departing from the spirit of the invention.

5 What I claim as new, and desire to secure by Letters Patent, is:

1. In thermostatically controlled switch mechanism, the combination of a switch device having a rocking current-controlling

10 element, lever means operatively engaging and supporting said element and operating, when rocked, to control the conditioning of said switch device, and a thermostatic element controlling the position of said lever means.

15 2. In thermostatically controlled switch mechanism, the combination of a switch device having a rocking current-controlling element, levers separate from and each oper-

20 atively engaging said element and constructed and arranged to rock said element when said levers are rocked, and a thermostatic element separate from said levers and controlling the position of said levers.

25 3. In thermostatically controlled switch mechanism, the combination of a switch device having a rocking current-controlling element, levers operatively engaging said element and by which said device is sup-30 ported, said levers being constructed and arranged to rock said element when said levers are rocked, and a thermostatic element controlling the position of said levers.

35 4. In thermostatically controlled switch mechanism, the combination of a holder, a contact-equipped receptacle on said holder, a gravity-actuated body in said receptacle for controlling the flow of current depending upon the position of the receptacle, and thermostatically controlled means for actuating said holder comprising levers separate from, and each pivotally connected with and supporting, said element and constructed and arranged to rock said element when said levers are rocked.

40 5. In thermostatically controlled switch mechanism, the combination of a switch device having a rocking current-controlling element, levers having deflected end portions offset relative to each other and at which they are pivoted to said element and support the latter, and a thermostatic element controlling the position of said levers.

45 6. In thermostatically controlled switch mechanism, the combination of a holder, a contact-equipped receptacle in said holder, a gravity-actuated body in said receptacle for controlling the flow of current depending on the position of the receptacle, levers supporting said holder and constructed and arranged to rock said holder when said levers are rocked, and a thermostatic element controlling the position of said levers.

50 7. In thermostatically controlled switch

mechanism, the combination of a switch device having a rocking current-controlling element, levers having deflected end portions offset relative to each other and at which they are pivoted to said element, and a 70 thermostatic element separate from said levers and controlling the position of said levers.

75 8. In thermostatically controlled switch mechanism, the combination of a holder, a contact-equipped receptacle in said holder, a gravity-actuated body in said receptacle for controlling the flow of current depending on the position of the receptacle, a pair of levers having deflected end portions offset 80 relative to each other and at which they are pivoted to said holder, and thermostatic bars engaging said levers and controlling the position thereof.

85 9. In thermostatically controlled switch mechanism, the combination of a switch device having a rocking current-controlling element, a pair of levers extending at an angle to said element and pivotally supported, said levers being pivotally connected 90 beyond their pivotal supports to said element and supporting the latter and constructed and arranged to rock said element when said levers are rocked, and a thermostatic element having portions engaging both 95 of said levers for controlling the position of said levers.

10. In thermostatically controlled switch mechanism, the combination of a switch device having a rocking current-controlling 100 element, and thermostatically controlled means for actuating said element comprising lever means operatively engaging and supporting said element and operating when rocked to control the condition of said switch 105 device.

11. In thermostatically controlled switch mechanism, the combination of a switch device having a rocking current-controlling element, and thermostatically controlled 110 means for actuating said element comprising levers separate from, and each pivotally connected with and supporting, said element and constructed and arranged to rock said element when said levers are rocked.

115 12. In thermostatically controlled switch mechanism, the combination of a switch device having a rocking current-controlling element, and thermostatically controlled means for actuating said element comprising 120 levers separate from, and each pivotally connected with, and supporting, said element, said levers extending generally in the same direction and having deflected ends at which said levers are pivoted to said element, the 125 parts being so constructed and arranged that said deflected ends, in the swinging of said levers, move at their pivotal connections with said element alternately to opposite sides of the median line of said set of levers.

13. In thermostatically controlled switch mechanism, the combination of a switch device having a rocking current-controlling element, pivoted levers extending generally in the same direction with ends thereof deflected and offset relative to each other, said levers being pivotally connected at said deflected ends with said element the parts being so constructed and arranged that said levers are adapted, in their operation, to move at their pivotal connections with said element alternately to opposite sides of the median line of said set of levers.
14. In thermostatically controlled switch mechanism, the combination of a switch device having a rocking current-controlling element, pivoted levers having deflected ends at which said levers are pivotally connected with said element, and thermostatic elements extending generally in the direction in which said levers extend and having deflected ends at which they engage the ends of said levers remote from said deflected portions of the latter. 15 20

OSCAR C. SCHROEDER.
